UNITED STATES PATENT OFFICE.

PRETEXTAT LECOMTE, OF CONSTANTINOPLE, TURKEY, ASSIGNOR OF
ONE-HALF TO LEWIS F. MIZZI, OF CONSTANTINOPLE, TURKEY.

ROTARY ENGINE.

SPECIFICATION forming part of Letters Patent No. 761,512, dated May 31, 1904.

Application filed April 27, 1903. Serial No. 154,533. (No model.)

To all whom it may concern:

Be it known that I, PRETEXTAT LECOMTE, a citizen of the Republic of France, residing at Constantinople, Turkey, have invented certain new and useful Improvements in or Relating to Rotary Motors, Pumps, or Engines, of which the following is a specification.

This invention relates to a rotary motor, pump, or engine the essential elements of which may be combined in such manner that it will work either with single or double expansion, each of the said elements comprising chiefly a cylinder with two covers, between which rotates a disk constituting, in combination with blades or ribs transversely movable in it, the piston for the said cylinder. The lateral edges of the said blades coöperate with the corresponding faces of the cylinder-covers, which are provided with symmetrical helical surfaces extending in opposite directions, said helical surfaces being separated by flat surfaces, at each side of which are respectively the inlet and exhaust openings merging into recesses in the said cam-surfaces. Admission and exhaust take place without the aid of any intermediate accessory parts, simply by the transverse shifting of the blades, which takes place under the influence of the rotation of the piston, the lateral edges of said blades always remaining in contact with the corresponding surfaces of the cylinder-covers and bringing about the expansion of the driving fluid at a moment comprised between the closing of the inlet and the opening of the exhaust. This construction may be used not only as motor, but also as a suction-pump or high-pressure fan for blast-furnaces and other purposes.

A rotary motor according to this invention, with two cylinders combined to obtain double expansion of the driving fluid, is illustrated, by way of example, in the accompanying drawings, in which—

Figure 1 is a view in elevation in longitudinal section through the axis of the small cylinder, the walls of the large cylinder being removed for the purpose of showing the arrangement of the parts in the interior thereof. Fig. 2 is a plan of Fig. 1, the upper por-

tion of the small cylinder being removed. 50 Fig. 3 is a vertical section on line A B of Fig. 1. Figs. 4, 5, and 6 are perspective views of the piston and covers of the large cylinder of this motor. Fig. 7 shows diagrammatically in development the position of the cylinder-covers and piston and illustrates the process of admission, expansion, and exhaust.

The two elements of this motor in which the fluid can simultaneously work at different pressures being similar except as regards 60 their dimensions, it will be sufficient to describe one of them in order to understand the construction of both. Each of the said elements is mainly constituted by a cylindrical body consisting of two half-cylinders *a b* bolted together. The cylinder thus constituted is closed by covers *c d*, bolted to the corresponding flanges of the half-cylinders *a b*.

Each cover *c d* has on its inner face two helical surfaces *e f*, which start from a projecting segmental flat surface *g* and extend therefrom in opposite directions and terminate at a segmental flat surface *h* identical with and diametrically opposite to the first one, *g*, but lying in a different plane and in 75 intaglio in the corresponding cover *c* or *d*.

The covers *c* and *d* are arranged on the cylinder in such a manner that their respective plane surfaces *g* and *h* face each other and in such manner that the interval between the 80 said plane surfaces and the corresponding helical surfaces is constituted by a space limited by surfaces sometimes plane and sometimes helical, but always parallel to each other.

The covers *c* and *d* are further provided with circumferential recesses *u v*, cut on each side of the projecting flat surfaces *g*, within the width of the helical surfaces *e f*. These grooves have the shape of curved wedges by 90 means of which the interior of the cylinder communicates with the exterior by orifices in which terminate at the orifices of the recesses *u* the inlet-pipes *x* for the fluid under pressure and at the orifices of the recesses *v* the 95 exhaust-pipes *y* for the same fluid after it has done its work.

The piston is constituted by a disk *p*, hav-

ing in its center two cylindrical projections *i i*, fitting into corresponding recesses *j j* in the center of the corresponding covers *c d*.

The piston *p* is mounted on a shaft *k*, passing through stuffing-boxes in the center of the covers *c d*. The thickness of the piston *p* is such that its parallel faces can freely rotate in the interval between the flat projecting surfaces *g*, while fitting them exactly.

10 The disk *p* is provided with radial slots *l*, extending from the cylindrical surface of the projections *i* to its circumference. In these slots *l* are arranged blades *m n o*, which can move in a direction parallel to the shaft *k* 15 during the rotation of the piston. These blades *m n o* are constructed so that they can expand in the direction of their width, so that their opposite edges press against the surfaces of the covers *c d* during the rotation of 20 the piston. For this purpose the blades are made of two similar plates *s t*, engaging with each other and capable of laterally sliding relatively to each other in the thickness of the piston *p*. These plates *s t* are provided 25 with interior recesses *q*, intended to receive springs *r*, which have the tendency to move them away from each other, and consequently to keep the opposite edges of the blades in contact with the covers *c d*. These 30 edges are preferably constituted by two bevel-surfaces, forming a hog's back and sloping in the direction corresponding to that of the helical surfaces *e f* for the purpose of causing them to coöperate efficiently with the said surfaces during the rotation of the piston.

In order to insure sufficient tightness of joint, two or three blades of the construction described may be used in each recess; but in that case they must be made of suitable thickness, and each blade then acts separately, 40 pressing with its edge on the corresponding surface of the helical cam, so that obturation takes place on a wider surface of the cam.

As already explained, the fluid is admitted 45 at each side through the covers *c d* by means of the pipes *x*, the exhaust taking place through the pipes *y*, the orifices of these inlet and exhaust pipes being, respectively, diametrically opposite each other, so that the 50 fluid acts simultaneously on each side of the piston, the operative area of the blades of the latter gradually increasing, as will be herein-after explained.

The working of the motor is as follows: 55 With reference to one side of the rotary piston *p* let it be assumed that the piston rotates in the direction indicated by the arrows, Figs. 3 and 7, and that the fluid has entered the compartment limited by the blade *m* and that 60 this blade has arrived at the bottom of the descending helical cam *e*—that is to say, at the intersection of this cam with the corresponding segmental flat surface *h*, Fig. 7. In that position the next blade *o* will already have en- 65 tirely passed the inlet-recess *u* and cut off the

admission of the fluid. The latter will then be contained in a triangular compartment, the oblique and lateral walls of which will be constituted by invariable surfaces which will form a number of points of abutment for the 70 fluid, and the base of which triangle will be formed by a movable surface on which the fluid will exercise pressure. As the compartment occupied by the fluid will increase in volume, owing to the movement of the piston, 75 the fluid will expand in that compartment limited by the blade *m* and at the same time exercise its driving action on the latter, thus causing the piston to rotate in the direction indicated. As soon as the blade *m* begins to 80 move on the segmental surface *h* and the next following blade *o* has completely closed the admission of the fluid the preceding blade *n* begins to open the exhaust, so that to the expansive force of the fluid acting behind the 85 blade *m* is added the action of the depression in the compartment in front in which the fluid acted previously, the working of the motor and the action of the fluid on the blade *m* without back pressure being thus insured. 90 The blade *m* on having reached the end of its travel on the flat segmental surface *h* travels on the ascending helical surface *f*, carrying with it a certain quantity of inert fluid, the volume of which remains the same. This 95 quantity escapes in its turn as soon as the blade *m* has uncovered the exhaust-orifice.

The same process as that described with reference to one side of the piston takes place on the other side of the piston, the two series 100 of operations alternating with each other. It follows, therefore, that the driving fluid will be admitted and exercise its pressure during the whole time of its admission to one side of this piston, the expansion of it taking place 105 in one of the compartments on the other side, and vice versa.

It follows from the preceding explanations that the admission, expansion, and exhaust of the driving fluid take place without the intervention of any accessory parts and are effected by the simple action of the blades in coöperation with corresponding lateral surfaces of the cylinder-covers, the arrangement of these surfaces being such that the blades 110 move transversely and alternately, so as to regulate all admission, expansion, and exhaust successively and alternately on each side of the piston carrying them. The expansion taking place in the small cylinder is not sufficiently complete to utilize the whole pressure of the fluid that passed through that cylinder, and the fluid on leaving that cylinder has sufficient force of expansion to enable it to act on driving-blades of larger area. This 115 additional force of expansion may be utilized in the manner shown in the construction illustrated in the drawings, in which the fluid escaping from the small cylinder by the pipes *y* is admitted into the large cylinder at 120 125 130

each side of the piston p and escapes at $w w$ after its pressure has been completely utilized in that cylinder. In this construction the pistons of both cylinders are keyed onto the same shaft, so that the motor thus acts like a reciprocating compound motor.

What I claim as my invention, and desire to secure by Letters Patent, is—

1. A rotary motor pump or engine comprising a cylindrical casing the lateral walls whereof are provided with helical cam-surfaces $e f$, diametrically opposite flat segmental surfaces $g h$ between said helical surfaces and wedge-shaped admission and exhaust recesses $u v$ one at each edge of the raised segmental surface with their deepest parts against such edges, in combination with a radially-slotted disk p

and a plurality of laterally-slidable and expansible piston-bearings $m n o$ mounted in the slots, substantially as set forth. 20

2. In a rotary engine of the kind described, a piston-disk comprising a shaft, a circular disk fast thereon, circular central guide-boxes on either side of said disk and radial piston-blade slots extending from the outer edge of the disk to the central guide-boxes, substantially as set forth. 25

In testimony whereof I have signed my name to this specification in the presence of two subscribing witnesses.
